UNITED STATES PATENT OFFICE

1,946,878

PROCESS AND APPARATUS FOR CON-
STRUCTING FABRIC PATTERN CARDSAuguste Pazziani and Albert Chalut, Geneva,
SwitzerlandApplication October 29, 1932, Serial No. 640,324,
and in Switzerland November 3, 1931

2 Claims. (Cl. 216—14)

This invention has for its object an improved process for the manufacture of fabric pattern or sample cards, that is to say, cards on which are attached series of samples or patterns of fabrics and apparatus for carrying out the process.

According to the process one places in contact with the samples an adhesive layer, such as adhesive paper, this sheet being itself placed in contact with the sheet of cardboard and we place 10 in contact with the latter a heating body which causes the samples to adhere to the cardboard by the intermediary of the said layer of material.

The annexed drawing diagrammatically illustrates by way of example a form of construction of an apparatus for carrying out the process.

Stacks of samples of fabric *a* are placed in a series of magazines such as *b* each stack being pressed by a spring *c* against narrow upper inwardly projecting rims or borders *d* of the magazines.

The magazines are arranged symmetrically in rows.

On the upper part of this device a sheet *e* 25 of adhesive paper is placed, then on this sheet *e* is placed the card *f*. A heating plate *g* is then applied on the whole and causes one of the faces of the adhesive paper to adhere to the cardboard and the other face of this paper to 30 adhere to the patterns. After some minutes it is sufficient to remove this heating plate when the card can be withdrawn ready for use being composed of cardboard, adhesive paper and patterns the adherence to the adhesive paper easily 35 overcoming the slight resistance offered by the projecting edges *d*.

What we claim as our invention and desire to secure by Letters Patent of the United States is:

1. A process for the construction of fabric sample cards consisting in placing in contact with the uppermost one of a stack of fabric samples 60 one surface of a sheet of adhesive material, placing the other surface of said sheet in contact with one face of a sheet of cardboard, and superposing on the other surface of said sheet of cardboard a heating and pressing plate, maintaining 65 the cardboard and adhesive sheet between the stack of fabric samples and the heating and pressing plate until the uppermost sample of the stack adheres to said adhesive sheet and until the latter dries, and finally removing said plate and sample 70 card.

2. An apparatus for mounting fabric samples on a sample card comprising a base, a series of spring members mounted on said base, a series of independent vertical magazines surrounding 75 said spring members adapted to contain stacks of samples supported on said spring members, said magazines being open at their top and bottom ends, inwardly directed rims at the top ends of said magazines, a heating and pressing plate 80 mounted above the magazines and adapted to cooperate with the tops of said magazines for causing a sheet of adhesive material to adhere to the uppermost samples in the magazines and to a sheet of cardboard placed with the adhesive 85 sheet between the tops of the magazines and said plate.
